CIGAR HEADER MECHANISM

James P. Durning, St. Albans, N. Y., assignor to
International Cigar Machinery Company, a corporation of New Jersey

Original application October 27, 1936, Serial No.
107,792. Divided and this application October
23, 1941, Serial No. 416,161.

4 Claims. (Cl. 131—29)

This invention relates to cigar machines, and more particularly to improvements in cigar header mechanisms therefor, and constitutes a division of my co-pending application, Serial No. 107,792, filed October 27, 1936, now Patent No. 2,290,171, issued July 21, 1942.

In the wrapping mechanism of existing machines it has been difficult to prevent waste, dust, sand, scraps of tobacco, and other unwanted materials commonly found in tobacco from accumulating on operative parts of the wrapping mechanism where it may cause possible clogging and/or excess wear of those parts. It has also been difficult to adjust important coacting elements of the wrapping mechanism because of the relative inaccessibility of the parts themselves and their operating members.

It is an object of my invention, therefore, to provide improved wrapper head forming mechanism such that the danger of access of deleterious and waste causing materials is substantially eliminated and make possible rapid and easy adjustment of these parts in order to adapt the wrapping mechanism for any desired type of bunch.

It is a further object of my invention to provide a novel and improved header cone device which can be rapidly adjusted and to so construct the header cone operating elements that any desired adjustments and replacements may be made in a minimum of time.

With these and other objects not specifically mentioned, in view, the invention consists of the combinations and constructions which will be hereinafter fully described, and then set forth in the claims hereunto appended.

In the accompanying drawings which form a part of this specification and in which like reference characters indicate the same or like parts:

Figure 1 is a partial plan view of Figure 2 omitting therefrom the header cone, the wrapper tension plate and its operating mechanism, and the flag trimmer and parts of its operating mechanism;

Figure 2 is an end view showing the cigar head rolling mechanism embodying my improved wrapper header cone device which coacts with the rolling unit and its associated cigar wrapping and finishing elements;

Figure 3 is a partial sectional view of the improved cigar header mechanism taken on line 3—3 of Figure 4;

Figure 4 is a sectional view taken on line 4—4 of Figure 1;

Figure 5 is a plan view of a detail of the header operating mechanism on a larger scale; and

Figure 6 is a view taken on line 6—6 of Figure 5.

Referring to the drawings, Figure 2 shows my improved header cone in operative relation to the tension plate, flag cutter and their operating

mechanisms. Tension plate 81, which guides a wrapper to a cigar bunch positioned for wrapping and maintains it under proper tension, includes a bracket 16 pivoted on a shaft 71 mounted in housing 11 which encloses a substantial part of the operating and driving mechanisms of the wrapping unit. A shaft 79 in the upper end of bracket 16 supports a frame member 80 pivotally mounted thereon to rock the tension plate 81 upward under the action of a spring (not shown), dependent upon the movement of cam 113 which is engaged by roller 84 secured by an eccentric pin 85 to arm 86. Cam 113 forms a part of arm 87 pivoted at 109 to an extension of frame 11. A pin and slot connection 110 to link 111 secured to arm 82 at 112 effects the movement of arm 87 through link 96 connected to crank arm 95. An adjusting screw 114 provided on a lug 115 of the arm 87 and engaging link 111 provides means for adjusting the movement of arm 87.

The flag cutter includes a stationary blade 116 secured to a bracket 117, adjustable on a shaft 118 together with a rotatable blade 119 fixed on the shaft 118 which is supported by a bracket arm 120 pivoted at 121 to the frame 15, which forms a part of housing 11 (see Figures 1, 3 and 5). An outside guard 11a secured to housing 11 by suitable means, not shown, encloses the flag cutter operating mechanism. Arm 120 is preferably loosely mounted on shaft 121 and in the embodiment shown moves up and down in accord with the movement of bracket 125 mentioned hereinafter. Lever 129 is formed with two arms 129a and 129b in order to facilitate adjustments of the header cone, which otherwise would be difficult due to the presence of the housing 11 which encloses a substantial part of the rolling unit operating mechanism including that which operates the header cone and flag trimmer.

Due to its improved construction and the open space provided by the arms 129a and 129b, a tool can be inserted through an opening in the housing 11 normally closed by hinged cover 14 (Figures 2 and 4) and any desired adjustments of cams 132 and 140 can readily be made in a minimum of time. A driven member 122, mounted on the shaft 118, is designed to be raised and rotated by a driving member 123, secured to a shaft 124 on the bracket 125 which is loose on a shaft 126 secured to the frame 15 at its bearing 127. The driving member or pulley 123, mounted with greater leverage than driven member 122 and continuously driven from another unit of the cigar machine (not shown), is raised when a spring-held finger 128, pivoted on one arm 129a of the lever 129 at 130, which is mounted on the shaft 126, engages a nose 131 of an adjustable cam 132 on the cam shaft 16. This construction permits of positive control of the depth of cut of the flag. When the pulley 123 is

50 a shaft 126 secured to the frame 15 at its bearing 127. The driving member or pulley 123, mounted with greater leverage than driven member 122 and continuously driven from another unit of the cigar machine (not shown), is raised when a spring-held finger 128, pivoted on one arm 129a of the lever 129 at 130, which is mounted on the shaft 126, engages a nose 131 of an adjustable cam 132 on the cam shaft 16. This construction permits of positive control of the depth of cut of the flag. When the pulley 123 is

raised it engages and lifts the driven member 122 to rotate it and the flag cutter blade 119, the result being more easily obtained due to the improved relation of the driving and driven members 122, 123 and leverages described. When bracket 125 is lowered at the close of the flag cutting operation, arm 120 also moves downwardly until an adjustable set screw 120a, carried thereon, engages a pin 15a fixed in frame 15, and thereby disconnects the drive between members 122 and 123. By means of this arrangement, excessive wear of the shaft of the driven member is eliminated since this member is merely raised against gravity into operative position. A lock screw 133 on arm 134a of lever 134 fixed to shaft 126, mounted to one side of the bracket 125, engages a lug 135 of the lever 125 providing for adjustment of the driving member 123 upward relative to rocking lever 134 by means of screw 133. The upward movement of driving member 123 is, therefore, effected by rocking lever 134 wherein arm 134b through engagement with set screw 136 on bracket 125 lifts the bracket 125 to an upper limit defined by the movement of lever 134 and the position of set screw 133. The adjusted positions of set screws 133, 136 allow movement of lever 134 relative to bracket 125 to control the time of engagement of driven member 122 and driving member 123.

The header cone 141 snaps rapidly into operation relative to header block 163 in order to control the application of the wrapper flag about the head end of a bunch being wrapped at substantially the same time that the knives move out of operative position when finger 128 drops off cam nose 131. A spring 161 (Figures 2, 3, 5 and 6) holds finger 128 against a stop 129c (Figure 1) formed on arm 129a of two-armed lever 129. This arrangement prevents locking or jamming between finger 128 and the tip 131 of cam 132 if for any reason it is desired to turn the machine back manually for adjustments or repairs. A screw 137, on the bracket 125, limits the movement of the member 123 relative to the housing 11. On the other arm 129b of the lever 129, a cam roller 138 is pivoted at 139 for coaction with the cam 140 to retract an adjustable header cone 141 carried by an arm 142, against the tension of spring 145 which normally urges the cone towards the head end of the bunch (Figures 1 and 2). The header cone 141, carried by an arm 142, is clamped to a stud 143 held by arm 144 adjustably and resiliently pivoted by a coil spring 145 on the pin 146 supported in the frame 15 at 147. An arm 148 fixed to the pin 146 and extending inwardly has a tip 149 which extends downwardly to rest on the cam surface 150 of the arm 129a of the lever 129 which transmits the cam motion to the header cone 141 away from the cigar. The coil spring 145 suitably anchored at 151 to a collar 152 fixed to the pin 146, which extends through the frame 15, and to a pin 153 on the frame 15 at 147 is enclosed in the housing 11 which eliminates the need for a separate housing. In this manner all of the operating mechanism of the header cone is enclosed by housing 11 and all adjustments are made outside the housing 11 and frame 15 by suitable adjustments to arm 144 and its related parts. The improvements apparent in this construction contribute to increased efficiency of operation and the ease with which adjustments may be made.

The excess paste, which in the operation of the flag cutter, drops and accumulates on the surrounding mechanism to the detriment of the affected parts and their operation is now caught 5 and diverted by a ledge 156 formed on the frame 15 as indicated in dot and dash lines (Figure 2) to a removable receptacle 157, suitably attached to the casing 11 at 158.

The invention above described may be varied in 10 construction within the scope of the claims, for the particular device, selected to illustrate the invention, is but one of many possible concrete embodiments of the same. It is not, therefore, to be restricted to the precise details of the structure shown and described.

What is claimed is:

1. In a cigar rolling mechanism, a header block, a header cone and means for moving said cone to and from heading position, said means comprising a resiliently mounted arm supporting said cone, a shaft for said arm, said shaft being secured in and projecting through a frame member, said arm being mounted on said shaft adjacent one side of said frame member, a second shaft mounted in said frame member, a two-armed lever secured to said second shaft adjacent the other side of said frame member, and means cooperating with said arms of said lever for effecting said movement.

2. In a cigar rolling mechanism having a frame including a housing on said frame, a header block, a header cone coacting with said block, and means for moving said cone to and from heading position, said means comprising a shaft extending through said frame and beneath the top of said housing, an arm supporting said cone secured outside of said frame and housing, a cam operated arm fixed to said shaft within said frame and housing, and a cam coacting with said last-named arm to move said cone.

3. In a cigar rolling mechanism having a frame member, a header cone movable into and out of coaction with a cigar bunch being wrapped to apply the flag end of a wrapper about the bunch, a shaft extending through said frame, a cone-supporting arm mounted on said shaft on one side of said frame member, a cone-operating arm mounted on said shaft on the other side of said frame member, a cone-operating cam, a two armed lever, a cam follower on one of said lever arms engaging said cam, and a cam surface on the other of said lever arms coacting with said cone-operating arm to move said cone out of heading position.

4. In a cigar rolling mechanism having a frame member, a header cone movable into and out of coaction with a cigar bunch being wrapped to apply the flag end of a wrapper about the bunch, a shaft extending through said frame member, a cone-supporting arm mounted on said shaft on one side of said frame member, resilient means normally tending to urge said cone into operative wrapper applying position, a cone-operating arm mounted on said shaft on the other side of said frame member, a cone-operating cam, a two armed lever, a cam follower on one of said lever arms engaging said cam, and a cam surface on the other of said lever arms coacting with said cone-operating arm to move said cone out of heading position.

JAMES P. DURNING.
